[57] CLAIM

The ornamental design for a traction support stand, as
shown and described.

DESCRIPTION

FIG. 1 is a perspective view of a traction support stand
showing my new design;

FIG. 2 is a side elevational view thereof, the opposite
side being a mirror image;

FIG. 3 is a top plan view thereof;

FIG. 4 is a bottom plan view thereof;

FIG. 5 is a front elevational view thereof; and

FIG. 6 is a rear elevational view thereof.

FIG. 1

FIG. 2

FIG. 5

FIG. 3
